UNITED STATES PATENT OFFICE.

CHARLES F. ARNHOBST, OF CHICAGO, ILLINOIS.

IGNITING GAS-BURNERS.

1,050,328.

Specification of Letters Patent. Patented Jan. 14, 1913.

Application filed January 19, 1912. Serial No. 672,183.

To all whom it may concern:

Be it known that I, CHARLES F. ARNHOBST, a citizen of the United States, and a resident of the city of Chicago, county of Cook, and State of Illinois, have invented 5 certain new and useful Improvements in Igniting Gas-Burners, of which the following is a specification.

My invention relates to improvements in 10 igniting gas burners by an electric spark, especially where it is required to ignite a series of burners.

A further object of my invention is to 15 provide an arrangement of parts that will offer a compact and practical construction and simple arrangement of electrical connections.

With these objects in view, my invention relates to the combinations and arrangements 20 of parts hereinafter described and claimed.

My invention will be best understood by 25 reference to the accompanying drawings forming a part of this specification, and in which—

Figure 1 is a conventional view of the arrangement of the burner, spark plug, switch mechanism, induction coil, and the corresponding electrical connections, the switch 30 mechanism being shown in section, Fig. 2 is a view looking down from line $\alpha-\alpha$ of Fig. 1, showing the single secondary bus bar and the series of separate contacts, also showing the connecting yokes for the secondary 35 circuits, and Fig. 3 is a similar view looking down from line $\gamma-\gamma$ of Fig. 1, showing the pair of primary bus bars and the lower yokes for closing the primary circuit.

The preferred form of construction of the 40 invention is illustrated in the accompanying drawings. Each of the gas burners 1 carries in a suitable manner an insulating bushing 2 at one side thereof. Inserted in said bushing 2 and adjustably secured by the locking 45 nuts 3 and 4 is a metallic rod 5 forming a spark gap 6 with the gas burner 1. The switch mechanism comprises a face plate 7, brackets 8 secured thereto extending vertically and supporting in a superposed relation two base plates 9 and 10 of insulating 50 material. The primary bus bars 11 and 12 are mounted upon the base plate 10. The secondary bus bar 13 and the series of separate contact points 14 are mounted upon the 55 base 9. A plurality of push button rods extend through the face plate 7 and the bases

9 and 10, and rest upon springs 16 supported by plates 16' secured to the under side of base plate 10. Upon each rod are secured yokes 17 and 18, the lower yoke 17 being adapted to connect the primary bus bars. Each of the upper yokes 18 connects a corresponding one of the contact plates 14 to the secondary bus bar 13. The induction coil 19 is of the usual form, comprising a 60 primary winding and a secondary winding. 65

20 is a three-celled battery.

Each one of the spark plugs 5 is connected to a corresponding one of the contact plates 14. The secondary bus bar 13 is connected 70 to a terminal of the secondary winding of the induction coil, the remaining terminal of the secondary winding being grounded. The primary bus bars are connected into the primary circuit of the induction coil, as 75 shown in Fig. 1.

In operation, when it is desired to ignite one of the burners, the gas being supplied thereto, the corresponding push button rod is pushed down. Its lower yoke 17 will 80 close the primary circuit of the induction coil, and its upper yoke 18 will connect the spark plug of the burner to the terminal of the secondary winding of the induction coil. Since the remaining terminal of the secondary 85 winding is grounded, a spark will be caused to jump across the spark gap at the burner and instantly ignite the gas.

While I have illustrated and described the preferred form of construction for carrying 90 my invention into effect, this is capable of variation and modification without departing from the spirit of the invention. I, therefore, do not wish to be limited to the exact details of construction set forth, but 95 desire to avail myself of such variations and modifications as come within the scope of the appended claims.

Having described my invention, what I claim as new and desire to secure by Letters Patent, is:

1. The combination with a plurality of insulating plates; of a pair of parallel bus bars mounted upon one of said plates; a bus bar mounted upon the remaining plate; 105 a plurality of contact elements arranged upon said last named plate and parallel to said last named bus bar; plunger rods reciprocating through said plates; and independent yokes mounted upon said plunger rods for simultaneous co-operation with the bus bars and contact plates aforesaid. 110

2. The combination with a pair of insulating plates; of parallel bus bars arranged upon one of said plates; contact plates and a bus bar arranged upon the remaining insulating plate; a contact yoke arranged adjacent to each insulating plate for coöperation with the contact elements and bus bars mounted thereon; and means for the simultaneous operation of each yoke coöperating with said parallel bus bars and its corresponding yoke coöperating with said bus bar and one contact plate.

3. The combination with a pair of insulating plates; of a bus bar and a plurality of contact plates mounted upon the upper insulated plate; a plurality of bus bars

mounted upon the lower insulating plate; yokes connecting the contact plates and bus bar of the upper plate and the bus bars of the lower plate; and means for simultaneously operating each yoke connecting said plurality of bus bars and the yoke immediately above it which connects said bus bar and one contact plate.

In testimony whereof I have signed my name to this specification in the presence of two subscribing witnesses.

CHARLES F. ARNHORST.
